RAIL BRACE

George Arnold, Shaker Heights, and Harry A. Schultz, Garfield Heights, Ohio, assignors to Cleveland Frog & Crossing Co., Cleveland, Ohio, a corporation of Ohio

Application February 15, 1950, Serial No. 144,226

5 Claims. (Cl. 238—292)

1 This invention relates to a rail brace such as is applied to a railroad rail to resist any tendency of the rail to turn outwardly from the center of the track and to clamp the rail to the tie plate, base plate or switch plate on which it rests, thus holding the rail against movements relative to the base plate, which base plate, in turn, is secured to a supporting tie as is well understood in the art.

Rail braces of the type contemplated by this invention are most frequently applied against the stock rails along side split switch points, but their use is not necessarily limited to such application.

Further, braces of this type are frequently made adjustable to compensate for variations in the dimensions of the rail, in the dimensions of the seat for the rail and brace in the base plate itself and also to afford a means of retightening the assembly after wear takes place.

Rail braces employed for this purpose generally have a portion which engages one of the sloping base flanges of the rail and the vertical web of the rail where it merges with the base flanges and a portion which engages the web beneath the rail head.

Heretofore rail braces have been secured to the base plates in rail clamping and bracing position by hold-down or clamping bolts carried by and extending vertically through openings in the base plates and braces.

In the use of the rail braces in track it sometimes occurs that the hold-down bolts become damaged or are sheared off, thus necessitating removing the rail brace and remounting the same with new hold-down bolts. Inasmuch as the practice has been to have the hold-down bolts carried by and extend through openings in the base plates with the heads of the bolts located between the base plates and the ties to which the plates are secured, it has been necessary, in order to remove the hold-down bolts, to first remove the base plates from the ties. This is a disadvantage in maintenance operations and consumes substantial time and labor. Furthermore, since the hold-down bolts are mounted in and carried by the base plates and extend through openings therein, it has been necessary to provide the base plates with openings. These openings in the base plates have been located in positions which coincide with that part of the base plates subject to the greatest strain in use. This location of the openings in the base plates has been occasioned by the fact that it is customary to provide the rail braces intermediate the side

walls of the braces with complementary hold-down bolt receiving openings.

As previously stated, rail braces heretofore used generally have had a portion which engages one of the sloping base flanges of the rail and the vertical web of the rail where it merges with the base flanges and a portion which engages the web beneath the rail head. Also the rail braces, as above pointed out, have been secured to the base plates in rail clamping and bracing position by vertical hold-down or clamping bolts extending through the base plates and braces. Difficulty has been experienced with the rail braces in use, in that the braces, when in track, tend to work downwardly of the sloping base flanges of the rails and away from the webs of the rails until the braces do not effectively clamp the rails to the base plates or brace the rails against tilting or moving away from the shoulders of the base plates.

Various arrangements have been employed to overcome this tendency of the rail braces to work away from the rails as, for instance, it has been usual to employ wedge members inserted between the rail braces and fixed abutments or back stops secured to the base plates, the function of the wedges being to force the braces toward the rails.

An object of the present invention is to provide a rail brace which is so constructed and is so secured to the base plate as to overcome all of the disadvantages inherent in the rail braces heretofore used.

More specifically an object of the present invention is to provide a rail brace and base plate construction such that the hold-down bolts can be applied to the brace and base plate without necessitating removing the base plate from the tie and in such manner that when the brace is installed it tends at all times and under track conditions to work toward the rail rather than away from the rail, thus insuring the maintenance of the necessary clamping and bracing relationship between the brace and the rail.

A further object is to provide a rail brace and base plate construction such that the brace can be more readily initially installed and after installation requires a minimum amount of maintenance since the brace will be maintained in position against the rail automatically but should it be necessary to remove the brace from the rail such removal can be accomplished expeditiously and without the necessity of removing the base plate from the tie.

A further object is to provide a rail brace and base plate construction as referred to in the preceding objects and which is so constructed as to

eliminate the necessity of employing tightening wedges.

A still further object is to provide a rail brace and base plate construction which includes improved and novel abutments or back stops that can be easily mounted on the base plate and which may be turned during their mounting to bring them adjustably into tight engagement with the rail brace, after which they can be rigidly secured in position.

Further and additional objects and advantages not hereinbefore specified will become apparent hereinafter during the detailed description of an embodiment of the invention.

The invention contemplates providing a rail brace adjacent to its opposite longitudinal side edges and beyond the side walls of the brace with means for operatively connecting the hold-down bolts with the brace and to utilize with such means hold-down bolts of a character that can be operatively connected to the base plate after the base plate has been secured to a tie and which hold-down bolts exert, in addition to a vertical hold-down clamping force, a component force tending to move the brace toward the rail and causing that portion of the brace which engages with one of the sloping base flanges of the rail to move upwardly of said base flange, as distinguished from the prior rail brace constructions wherein there is a tendency for the rail brace to move downwardly of the sloping base flange of the rail and work loose from proper and effective rail clamping and bracing position.

Referring to the accompanying drawing illustrating an embodiment of the invention,

Fig. 1 is a transverse sectional view through a rail mounted on a base plate and clamped and braced thereagainst by a rail brace, the latter and the base plate being shown in side elevation.

Fig. 2 is a horizontal sectional view through the web of the rail shown in Fig. 1, with the base plate, the base flanges of the rail and the rail brace shown in plan, one of the hold-down bolts and its nut being omitted.

Fig. 3 is a partial elevational and partial sectional view of the rail, base plate and rail brace; the base plate being illustrated as secured to a tie and the sectional and elevational portions being taken along or looking from the irregular line 3-3 of Fig. 2, looking in the direction of the arrows.

Fig. 4 is a fragmentary sectional view taken substantially on line 4-4 of Fig. 2, looking in the direction of the arrows.

Fig. 5 is a detached side elevational view of the base plate, and

Fig. 6 is a detached elevational view of one of the abutments or back stops shown in Figs. 1, 2 and 3.

The rail brace is employed with a railway rail indicated generally at 10 and comprising the usual base flanges 11 provided on their upper sides with downwardly sloping surfaces 12. A vertically extending web 13 interconnects the rail base with the rail head 14. The rail is supported on a base plate 15 which in turn is secured to a tie 16 by spikes or other suitable means, not shown, as it is well known in the art and extending through suitable openings 17 formed in the base plate. The base plate 15 on its upper side is provided with a recess 15a in which the base of the rail is located, with the left hand side of the rail, as viewed in the drawing, engaging the base plate shoulder 15b at the left hand end of the recess.

The rail brace is for the purpose of clamping and holding the rail in proper position with respect to the base plate so that the left hand base flange 11 of the rail firmly engages the base plate shoulder 15b and in order to prevent relative movements of the rail with respect to the base plate. This is the usual function of a rail brace as already explained.

The rail brace comprises a brace block indicated generally by the letter B and this block may be formed as a casting, forging or in any suitable manner as will be well understood in the art. The brace block B comprises a solid unbroken upper surface portion 18 which extends from just under the rail head 14 downwardly and outwardly laterally from the rail to the base plate 15 at a point spaced to the right of the right hand end of the recess 15a in the base plate as viewed in the drawings.

The block B further includes an intermediate downwardly extending rib 18a formed integral with the underside of the surface portion 18 and contacting the downwardly sloping surface 12 of the right hand rail base flange 11. The block B has side walls 19 and 20 which extend downwardly and slightly divergently with respect to each other. The side walls merge into upwardly extending flange portions 21 and flange portions 22 which extend outwardly from the portions 21. The flange portions 21 and 22 are integrally interconnected by curved flange portions 23 which engage the sloping upper surface 12 of the rail base flange 11. The surface portion 18, the rib 18a, side walls 19 and 20 and flange portions 21 integrally merge with a portion 23 that engages the rail web 13 just below the rail head 14 and extends the full width of the rail brace B. The rail web 13 just below the head 14 is contacted by the portion 23 and the upper surface 12 of rail base flange 11 is contacted at three spaced points by the flange portions 23 and 22 and by the rib 18a. There is clearance between the rail and rail brace except for the contact zones referred to above. The underside of the portion 18 and of the flange portions 22 at their outer ends remote from the rail bear upon the base plate 15 with a continuous bearing contact as indicated at 24.

The surface portion 18, side walls 19 and 20, and the flange portions 22 integrally merge into conical-like bosses 25 which have hollow downwardly divergent interiors. The upper surfaces 26 of the bosses 25 are parallel to each other and are inclined downwardly to the horizontal so as to be substantially parallel to the inclined surface 12 of the rail base flange 11. The upper surfaces 26 of the bosses 25 are provided with hold-down bolt openings 27.

The flange portions 22 of the rail brace are provided at the location of the bosses 25 and on the opposite sides of the rail brace with depending lugs 28 which when the brace is installed lie along side of and engage the opposite longitudinal sides of the base plate 15 and prevent the brace from shifting sidewise should one of the hold-down bolts break. The lugs 28 are located so as to lie outwardly of and conceal portions of the hold-down bolts.

The opposite longitudinal edges of the base plate 15 are provided with semi-cylindrical recesses 29 which communicate at their upper ends with vertical slots 30 that underlie the bosses 25. The hold-down bolts employed with the brace have semi-cylindrical heads 31 which can be engaged in the recesses 29 with a knuckle-like engagement. The hold-down bolts further

include straight shank portions 32 extending from the heads 31 through the straight slots 30 in the base plate, there being a substantial clearance between the shank portions 32 and the wall of said slot. The holdown bolts further include outer shank portions 33 integral with the portions 32 and inclined to the vertical so as to be substantially perpendicular to the downwardly sloping surface 12 of the right hand base flange 11. The shank portions 33 of the holdown bolts extend through the openings 27 in the bosses 25 and are provided with threads so holdown nuts 34 can be screwed thereon. The nuts 34 include closed heads 35 and sleeves 36 with annular flanges 37 intermediate the heads and sleeves. When the nuts 34 are screwed downwardly on the hold-down bolts the flanges 37 clamp between them and the upper surfaces 26 of the bosses 25 spring washers 38.

It will be seen that since the recesses 29 and slots 30 are located in the longitudinal sides of the base plate 15 and the bosses 25 are on the flange portions 22 of the block B the heads 31 and straight shank portions 32 of the hold-down bolts can be inserted respectively in the recesses and slots of the base plate after it is secured to the tie and before the block is applied to the rail, since the block can be installed against the rail without interference from the bolts and during which installation the straight shank portions 33 of the bolts can be passed through the bosses 25. Whenever necessary or desirable the hold-down bolts can be removed and replaced without disturbing the connection of the base plate 15 to the tie 16 since the heads 31 and the shank portions 32 of the bolts can be passed into and removed from the recesses 29 and slots 30 in the sides of the base plate.

As already pointed out, when the hold-down nuts 34 are tightened during the installation of the brace the heavy spring washers 38 are forced by the nut flanges 37 into engagement with the inclined upper end surfaces 26 of the bosses 25 and the nuts act through the washers to produce a hold-down force or pressure on the bosses and the block that provides a force component tending to urge the block B toward the rail web 13 and to cause it to ride upwardly on the downwardly sloping surface 12 of the rail base flange 11, in addition to causing it at 24 to firmly contact and press downwardly on the upper surface of the base plate 15 beyond the recess in the plate. The tendency of the rail brace when installed to ride upwardly on the base flange and toward the rail web at all times overcomes the tendency present in the heretofore used rail braces to work away from the rail and which latter tendency requires the use of tightening wedges that the present construction avoids. This advantage is accomplished by having the hold-down bolts provided with the angularly disposed or inclined shank portions 33 while the upper surfaces 26 of the bosses 25 are inclined sufficiently to be substantially parallel to the downwardly sloping surface 12 of the rail base flange 11. Therefore when the nuts 34 are screwed down on the holdown bolts the heavy spring washers 38 are held against the surfaces 26 and produce force components acting on the block B to hold the block down firmly against vertical movement and also to constantly urge the block toward the rail and upwardly of the surface 12 of the rail base flange 11.

The block B of the rail brace when once installed will always be held in proper engagement

with the rail and will exert thereon the requisite forces for holding the base of the rail firmly against the base plate 15 with the left hand end of the base tightly against the left hand end 15b of the recess in the base plate as viewed in the drawing. In addition, the portion 23 of the block will always be held tightly against the web 13 of the rail and due to the clearance between said portion and the underside of the rail head there will be no tendency for the block to produce a tilting or rocking movement of the rail since only a horizontal pressure is effected by the portion 23 against the rail web and the left hand base flange 11 is held firmly against the left hand end of the recess in the base plate.

The rail brace construction embodying the present invention effects the economy of eliminating the necessity for using tightening wedges in conjunction with the rail brace and which wedges ordinarily are interposed between the rail brace and fixed abutments formed on the base plate.

Although abutments or back stops are not necessary in a construction such as has been described, it may be advantageous to employ the same as additional assurance that the rail brace will be held in proper tight engagement with the rail, particularly should wear occur between any of the parts. A novel form of abutment or back stop is illustrated herein and which can be mounted in any one of several different turned positions to adjust it tightly against the rail brace.

The abutment is illustrated as comprising a square or polygonal head 39 from the flat under surface of which extends a cylindrical post 40 that is disposed eccentrically with respect to the center of the head 39. A tubular opening 41 extends through the head 39 and post 40. The base plate 15 intermediate its longitudinal side edges is provided with openings 42 therethrough and which openings are sized so as to rotatably interfit the posts 40 of the abutments or back stops when said posts are inserted into the openings with the heads 39 in engagement with the upper side of the base plate 15.

Due to the off center or eccentric location of the post 40 it will be seen that the back stops can be rotated to selectively bring one or the other of their side edges into contact with the rail brace thus assuring a range of adjustments such that the back stops will tightly engage the rail brace when the latter is mounted in position against the rail.

As illustrated, the back stops are so constructed that they have four different positions of rotative adjustment which should be sufficient to provide the tight engagement referred to and also to take care of slight dimensional inaccuracies.

When the rail brace has been installed against the rail and the back stops or abutments adjusted to effect the proper tight engagement with the rail brace the back stops or abutments can then be secured in such position by suitable means as, for instance, the headed screws 42a passed downwardly through the tubular opening 41 and into the tie 16 as clearly shown in Fig. 3.

From the foregoing description of an embodiment of the invention it will be clear that the present invention overcomes the disadvantages heretofore existing in rail braces and which disadvantages were fully set forth at the commencement of this specification.

Although a preferred embodiment of the invention has been illustrated and described herein

it will be understood that the invention is susceptible of various modifications and adaptations within the scope of the appended claims.

Having thus described our invention, we claim:

1. In a rail brace construction for use with a rail of the type having a head, base flanges provided with downwardly sloping upper surfaces and a web interconnecting the head and base flanges, and with a base plate secured to a tie and having opposite longitudinal side edges and upon which plate the base flanges of the rail are supported; said construction comprising a block having a first part located adjacent to the rail web and a second part extending laterally from said first part and overlying the base plate and having its outer end engaging the upper side of the base plate but being vertically spaced above said base plate intermediate said first part and the outer end of the second part, said parts including a portion engaging the rail web adjacent to but beneath the head thereof and a portion engaging the downwardly sloping upper surface of one of the rail base flanges, said laterally extending second part having opposite longitudinal edges provided with bosses for the hold-down bolts and when the block is installed against the rail located above the opposite longitudinal edges of the base plate and provided on their upper ends with downwardly inclined surfaces substantially parallel to the downwardly sloping upper surface of the said one rail base flange, and hold-down bolts mounted in said bosses and having threaded shank portions inclined to the vertical and substantially perpendicular to the said downwardly inclined surfaces on the upper ends of said bosses and mounting spring washers and hold down nuts which react against the said downwardly inclined surfaces, said bolts having their lower ends provided with head portions, and said base plate being provided at its opposite longitudinal edges with cavities in which said bolt heads interfit whereby said bolts are removably interconnected with the opposite longitudinal edges of the base plate when the latter is secured to a tie.

2. A rail brace and supporting means comprising a base plate which is secured to a tie to have its longitudinal side edges extend longitudinally of the tie and is provided on its upper side with a fixed abutment which is engaged by one of the two base flanges of a rail and which flanges are supported by the base plate and have downwardly sloping upper surfaces, the rail being of the type having a head and a web interconnecting the head and the base flanges, a block on said base plate and having integral parts, one of which lies adjacent to and extends vertically of the rail web and the other of which overlies said base plate and extends laterally from

the rail web and is provided at its outer end with a portion engaging said base plate, said parts having portions engaging the rail web adjacent to and below the rail head and the downwardly sloping upper surface of the other of the two base flanges of the rail, the part which overlies the base plate being provided on its opposite longitudinal edges with bosses overlying the longitudinal side edges of the base plate and through which bosses hold-down bolts extend, said bosses being provided on their upper ends with downwardly inclined surfaces substantially parallel to the downwardly sloping upper surface of said other base flange of the rail, hold-down bolts having heads at their lower ends, said base plate being provided at its opposite longitudinal side edges with cavities receiving said bolt heads whereby said bolts are connected to the opposite longitudinal side edges of said base plate, said bolts being provided with shank portions extending through said bosses and inclined to the vertical and substantially perpendicular to the downwardly inclined surfaces on the upper ends of said bosses, and nuts on said bolts which when screwed down thereon react against said downwardly inclined surfaces to produce hold-down forces on said block including a component urging said block toward said rail and upwardly of the downwardly sloping upper surface of said other base flange of the rail.

3. A rail brace and supporting means as defined in claim 2 and wherein the part of the block which overlies the base plate is provided on its opposite longitudinal edges with depending lugs engaging the opposite longitudinal side edges of the base plate.

4. A rail brace and supporting means as defined in claim 2 and wherein said part of said block which overlies said base plate includes side walls and outwardly thereof flanges which overlie the opposite longitudinal edges of said base plate, while said walls and flanges integrally merge into said bosses.

5. A rail brace and supporting means as defined in claim 2 and wherein said base plate is provided in its opposite longitudinal edges with recesses communicating with upwardly extending slots, while said hold-down bolts have heads detachably engaged in said recesses, and straight shank portions extending through said slots and integral with said inclined shank portions.
